UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL CONNECTER DEVICE.

Application filed February 17, 1921. Serial No. 445,587.

My invention relates to electrical connector devices, and more particularly to electrical connector devices for use with outlet boxes.

5 One of the objects of my invention is to provide improved means whereby the shell contact of a socket may be securely held in position with respect to the wiring base without falling out when the securing ring or 10 shade holder is removed, or being loosened up when the lamp is unscrewed.

A further object of my invention is to provide an electrical connector device which will be simple and compact in construction and 15 durable and efficient in use.

Further objects will appear from the detailed description to follow and from the appended claims.

In the drawings in which an embodiment 20 of my invention is shown—

Fig. 1 is an axial sectional view through an outlet box and electrical connector device;

Fig. 2 is a bottom plan view of Fig. 1 with certain parts removed;

25 Fig. 3 is a section on the line 3—3 of Fig. 2;

Fig. 4 is a side elevation of a part of the electrical connector device;

Fig. 5 is a top plan view of a receptacle member provided with Hubbell type contacts;

Fig. 6 is a side elevation of Fig. 5;

Fig. 7 is a side elevational view showing an electrical connector having a screw shell 35 contact;

Fig. 8 is a bottom plan view showing another form of combination wiring base and contact device; and

Fig. 9 is a section on the line 9—9 of 40 Fig. 8.

Referring to Figs. 1 to 6 inclusive, the construction shown therein comprises an outlet box 10, a fixed combination wiring base and connector member 11, a combination receptacle and contact member 12, a combination plug-in and wiring terminal device 13, and a fixture supporting member 14. The plug-in device 13 and fixture supporting device 14 are detachably secured in position with respect to the receptacle member 13, by means of a swivel ring which is screwed into a fixed ring portion 16 formed on the lower skirt portion of a cup-shaped sheet metal member 17, which serves as a housing for the mem-

ber 11. The member 17 also serves as a support for the receptacle 12 which as shown in Fig. 6 is provided with a helical thread portion 18, whereby this receptacle portion can be screwed into the screw-threaded skirt portion 16. This screw-threaded connection 60 holds the receptacle portion in place even when the ring 15 is screwed out and the plug-in portion 13 and fixture supporting portion 14 are detached.

The detachable screw-threaded connection 65 between the receptacle portion 12 and the threaded skirt portion 16 enables this receptacle portion to be removed and a receptacle portion 19 (Fig. 7) of a different type to be substituted therefor.

70 The assembly including the wiring base 11, the receptacle member 12, the plug-in device 13, and the fixture supporting device 14 is supported in position with respect to the outlet box 10, by means of a transversely extending stamping 20 having foot portions 21 secured to ears 22 of the outlet box by means of screws 23. A face-plate 24 is provided for the outlet box. This may be secured in position by threading it on to the threaded 75 skirt portion 16. For this purpose the face-plate 24 is provided with an integral inwardly extending threaded portion 25, which can be threaded on the outside of the threaded skirt portion 16.

80 For holding the wiring base 11 in position in the cup-shaped member 17, a pair of spring fingers 26 are provided having inwardly bent tips 27, which extend into recesses in the insulating base 28. The spring 85 fingers 26 may be formed as parts of an integral sheet metal strap secured to the transversely-extending straps 20 by means of rivets 29. These rivets 29 also serve to hold the cup-shaped member 17 in place on the strap 90 20. The central portion of the strap 20 is offset with respect to the foot portions 21, to bring the wiring base 11 in the proper position.

95 The wiring base 11 is provided with wiring terminals 30 for the conductors 31 and with center and side contacts 32 and 33 electrically connected with the wiring terminals 30 respectively. The binding plates of the wiring terminals 30 are held in place on the 100 insulating base 28 by means of screws 34. The center and side contacts 32 and 33 are 105 provided with base portions which are held

underneath the binding plates of the wiring terminals 30, whereby the contacts are held in position on the insulating base 28. The side contact members 33 have two laterally extending wing contact portions 35. The cup-shaped sheet metal member 17 is provided with openings 35^a for the conductors 31 which lead to the wiring terminals 30.

The insulating base 36 of the receptacle member 12 is provided with recesses 37, in which are located spring contact fingers 38 and 39. The spring contact finger 38 is secured to a ring contact member 40 (Fig. 5). This ring contact member 40 is so positioned that it will make contact with the side contact members 35 of the wiring base 11, when the receptacle member 12 is screwed into the threaded ring 16. The ring contact 40 may be secured in position on the insulating base 36 by means of eyelets 41. The spring contact finger 38 may be secured to the ring contact 40 by means of inwardly extending eyelet portion 42 formed integral with the ring contact 40. The spring contact finger 39 is secured in place on the insulating base 36 by means of a centrally located eyelet 43, which also serves as a center contact for engagement with the center contact 32 of the wiring base 11. It will be noted that the contacts 32, 33, 40 and 43 all lie substantially in the plane of the meeting faces of the members 11 and 12 whereby compact construction is secured which enables the device to be used in a shallow outlet box.

35 The insulating base 44 of the plug-in device 13 has mounted thereon a pair of contact blades 45 for engagement with the contact fingers 38 and 39 respectively, of the receptacle portion 12. These contact blades 44 and 45 are provided with suitable wiring terminals 45^a for the feed wires for the supporting fixture.

The hook 46 of the fixture supporting device 14 is secured to a supporting plate 47 which is supported by the inwardly extending flange of the screw-threaded ring 15. The supporting plate 47 has a central opening for the feed wires for the fixture. A cushioning washer 48 of fibre or other suitable material is provided between the supporting plate 47 and the inwardly extending flange of the threaded ring 15.

It will be noted when the ring is unscrewed, and the plug-in device 13 and fixture supporting device 14 removed, that the receptacle member 13 will still be held in place because of its threaded engagement with the fixed screw ring 16.

As previously stated, the receptacle 12 can be unscrewed from the fixed screw-threaded ring 16 and a receptacle member 19 (Fig. 7) of a different type may be substituted therefor. The insulating base 49 of this type receptacle may be provided with 65 a helical thread portion 50, similar to the

helical thread portion 18 of the receptacle 12, which will enable this receptacle 19 to be screwed into the fixed threaded ring 16.

This receptacle 19 is provided with a screw shell contact 51. The insulating base 49 has an opening through it, so that the center contact of a lamp which is screwed into the screw shell contact 51 can engage directly the center contact 32 of the wiring base and contact member 11. This avoids the necessity of providing an additional center contact for the receptacle member 19. As shown in Figs. 7 and 9, the inner portion of this threaded shell contact 51 engages the contact portions 35 of the side contact member 33 when the receptacle portion 19 is screwed into the cup 17.

A shade holder 52 may be screwed inside the threaded ring 16. This shade holder 52 may be used to prevent the receptacle 19 from becoming unscrewed when the lamp is being screwed out of the socket. For this purpose the upper edge 53 of the shade holder 52 is made to extend upwardly far enough to engage underneath a shoulder 54. Any unscrewing tendency of the receptacle 19 caused by the unscrewing of the lamp would be resisted by the engagement of the shoulder 54 with the upper edge of the shade holder 52.

The combination wiring base and contact member shown in Fig. 8 is substantially the same as the corresponding member 11 shown in Fig. 1, except in Fig. 8 additional binding screws are provided whereby a branch connection may be led off from this wiring base. The insulating base 28, the contacts 32 and 33, and the securing screw 34 may be the same as in the construction shown in Fig. 1. The binding plates, 55, however, are made wider so that a pair of binding screws 56 may be screwed into each one of these binding plates whereby provision is made for a branch connection.

Having thus described my invention, what I claim as new and desire to secure by Letters Patent of the United States is:

1. A ceiling unit comprising an inverted sheet metal cup, a metal strap having means whereby it may be secured to extend across an outlet box, said strap having its central portion extending across and secured to the bottom of said sheet metal cup, a combination wiring base and contact member seated in the inner end of said cup, and a contact member having contacts for engaging the contacts of said combination member and affording circuit connections to a translating device, said contact member being detachably mounted in the outer part of said metal cup.

2. A ceiling outlet unit comprising an inverted sheet metal cup having cylindrical screw threaded sides, a combination wiring base and contact member seated in the inner

end of said cup, a contact member comprising an insulating base and contacts mounted thereon for detachably engaging the contacts of said combination member and affording circuit connections for a translating device, said insulating base having a threaded engagement with the threads on the cup, whereby it may be screwed into said cup and held by said threads, and additional retaining means for said insulating base, comprising a screw threaded metal ring also having threaded engagement with the threads of the cup and engaging said insulating base. 10

In witness whereof, I have hereunto subscribed my name.

REUBEN B. BENJAMIN.
